(57) **CLAIM**

The ornamental design for a portable power tool body, as shown and described.

DESCRIPTION

FIG. 1 is a front, left, and top perspective view of a portable power tool body in accordance with our new design; FIG. 2 is a rear, right, and top perspective view of the portable power tool body in accordance with our new design;

FIG. 3 is a front elevational view of the portable power tool body in accordance with our new design;

FIG. 4 is a rear elevational view of the portable power tool body in accordance with our new design;

FIG. 5 is a top plan view of the portable power tool body in accordance with our new design;

FIG. 6 is a bottom plan view of the portable power tool body in accordance with our new design;

FIG. 7 is a left side elevational view of the portable power tool body in accordance with our new design;

FIG. 8 is a right side elevational view of the portable power tool body in accordance with our new design; and,

FIG. 9 is an enlarged rear and bottom perspective view of the portable power tool body in accordance with our new design illustrating the configuration of the bottom surface.

The broken lines in the drawings illustrate portions of the portable power tool body which form no part of the claimed design. The dash dot dash lines represent the boundary of the claimed design and form no part of the claimed design.
